UNITED STATES PATENT OFFICE

121,924

DESIGN FOR AN AERIAL TOY

Joseph Kerezi, Detroit, Mich.

Application May 20, 1940, Serial No. 92,469

Term of patent 7 years

To all whom it may concern:

Be it known that I, Joseph Kerezi, a citizen of the United States, residing at Detroit, in the county of Wayne and State of Michigan, have invented a new, original, and ornamental Design for an Aerial Toy, of which the following is a specification, reference being had therein to the accompanying drawing, forming part thereof.

Fig. 1 is a side elevational view of an aerial toy, showing my new design, and

Fig. 2 is a plan view thereof.

I claim:

The ornamental design for an aerial toy, as shown.

JOSEPH KEREZI.
